UNITED STATES PATENT OFFICE

LEE HIRSCH, OF NEW YORK, N. Y.

DESIGN FOR A RING SETTING

Application filed November 9, 1929. Serial No. 33,391. Term of patent 14 years.

To all whom it may concern:

Be it known that I, LEE HIRSCH, a citizen of the United States, and a resident of New York, in the county of New York and State of New York, have invented a new, original, and ornamental Design for a Ring Setting, of which the following is a specification, reference being had to the accompanying drawing, forming a part hereof, and in which—constituting my design shown as applied to a finger ring which is indicated in dotted lines.

I claim:

The ornamental design for a ring setting, substantially as shown and described.

LEE HIRSCH.
